UNITED STATES PATENT OFFICE.

ANTHONY J. KNILL, OF CICERO, ILLINOIS.

RADIO SOCKET AND TUBE.

Application filed October 12, 1927. Serial No. 225,771.

The present invention relates to an improved radio socket; that is, an improved and especially designed socket constructed for cooperation with a radio tube having a 5 reconstructed base.

What I propose is a structure of this kind which fastens the tube in the socket in a firm and efficient manner, the arrangement being such as to obviate the usual bayonet slot and 10 pin connection such as requires relative rotation of the tube to the base on the socket.

The details constituting the novelty of the annexed claims will become more readily apparent from the following description and 15 drawing.

In the drawing:—

Figure 1 is an elevational view of the revised tube and the especially designed socket in which it is fitted.

20 Figure 2 is a sectional view of the same.

Figure 3 is a top plan view of the mounting or socket per se.

Referring now to the drawing, by numerals, it will be observed that the reference character 4 designates generally the improved 25 mounting or socket which includes the attaching base 5 of customary design, and an up-standing socket 6. In the present instance this socket is formed at its top with an out-

30 standing marginal flange 7 which functions as a stop. On one side it is formed with a vertical elongated notch 8 which constitutes a guide.

Embedded or otherwise fastened to the base 35 are conductor strips 9 having their inner ends extending into the socket and terminating in rigid conical projections 10 providing contacts. These are arranged as shown in Figure 3 so that they are in proper circumferentially-spaced relation.

The radio tube is generally represented by the reference character 11, and the base 12 thereof is provided with a guide pin 13 receivable in the notch 8. In addition it is 40 formed with screw threads 14. The threads 14 are adapted to be engaged with internal threads on a coupling collar 15 fitted on the socket 6. Incidentally this collar is formed at its bottom with an inturned flange 15 which engages the flange 7 on the socket. The depending terminals 16 are formed in 45 their bottoms with conical recesses which fit

down over the correspondingly shaped contacts 10. It might also be mentioned that the aforesaid conductor strips 9 are extended out 55 beyond one edge of the base to facilitate the connection of wires. In practice these will be marked so that the proper wires can be readily connected therewith.

In inserting the tube in this structure it is 60 simply placed straight down in a vertical direction, the pin 13 being placed in the guide notch 8. Then the collar 15 is slipped up on the socket and engaged with the threads 14 in a rotary manner. This feeds the tube down 65 so that the conical recesses in the lower ends of the terminals or contacts 15 telescopically receive the correspondingly shaped contacts on the conductor strips 9. In this way the contact of the tube and base can be brought 70 into firm engagement to overcome accidental displacement and to insure a good electrical connection free from vibration and shifting. The advantages of a structure of this kind will be quite clear to persons familiar with 75 inventions of this class. Therefore, a more lengthy description is believed unnecessary.

Minor changes in shape, size, and rearrangement of details coming within the scope of the adjoined claims may be resorted to if 80 desired.

Having thus described the invention, what I claim as new is:—

1. A radio tube mounting comprising a base having a socket, rigid electrical contacts 85 on said base located within the area of said socket, said socket being provided at its upper end on one side with a guide notch, a radio tube telescopically fitted into said socket and having a pin movable vertically down into 90 said notch to align and bring the contacts on the tube into electrical connection with the contacts on the base and coacting means between the tube and socket for holding the tube in the socket, said coacting means comprising 95 a rotary screw threaded collar connection between the socket and base portion of the tube.

2. As a new product of manufacture, a radio tube mounting comprising a base having an upstanding socket provided at its top with 100 a marginal outstanding flange and formed on one side with a guide notch disposed vertically, conductor strips embedded in said base having their inner ends extending into the

socket and terminating in circumferentially spaced upstanding conical contacts, and a screw threaded collar fitted on said socket and having a flange engaging the flange on the 5 socket, together with a radio tube having a base portion fitting in said socket and provided with screw threads connected with the

screw threads on said collar, said base portion also having depending contact pins provided in their bottoms with conical recesses for reception of the aforesaid conical contacts. 10

In testimony whereof I affix my signature.

ANTHONY J. KNILL.
